UNITED STATES PATENT OFFICE.

THOMAS P. HARDY, OF NEW YORK, N. Y.

STEAM-RADIATOR.

SPECIFICATION forming part of Letters Patent No. 330,696, dated November 17, 1885.

Application filed January 15, 1885. Serial No. 152,989. (No model.)

To all whom it may concern:

Be it known that I, THOMAS P. HARDY, a citizen of the United States, residing at New York, in the county and State of New York, 5 have invented new and useful Improvements in Steam-Radiators, of which the following is a specification.

The object of this invention is to apply a diaphragm to a radiator-tube, the body of 10 which has a larger diameter than its foot, and also to increase the radiating-surface of the tube.

The object of my invention I accomplish in 15 the manner and by the means hereinafter described and claimed, reference being made to the accompanying drawings, in which—

Figure 1 represents a horizontal section in the plane $x x$, Fig. 2. Fig. 2 is a vertical section in the plane $y y$, Fig. 1.

20 Similar letters indicate corresponding parts.

In the drawings, the letter A designates the body of a radiator-tube, which is provided with a foot, B, threaded on its outer surface, so that the tube can be secured in the base C.

25 The inside diameter of the foot B is smaller than that of the body A, so as to increase the radiating-surface of the tube, and on the inner surface of the body A are formed or secured grooved projections $a a$, diametrically opposite to each other, as shown in Fig. 1. These

30 projections extend inward slightly beyond the inner surface of the foot B, and they are intended to receive and retain the diaphragm D. This diaphragm must be introduced through

35 the foot B, there being no other passage leading into the body A, and, since the inside diameter of the foot is smaller than that of the body A, it will be readily seen that the diaphragm, after having been pushed up into the

40 body, would have no support if it were not for the grooved projections $a a$. In pushing up the diaphragm care must be taken that the edges of the same enter the grooves of the

45 projections.

The width of the diaphragm must be somewhat greater than the inside diameter of the foot B, and after said diaphragm has been pushed up into the grooves of the projections it assumes the position shown in Fig. 1, and is retained by its own elasticity. In order to 50 effect this retention of the diaphragm by its own elasticity, it is necessary that the distance between the grooves into which the diaphragm slides is less than the width of the diaphragm.

55 With the body A of my tube I have combined a series of lateral chambers, E, which open into the body of the tube and materially increase the radiating-surface of the same. The lateral chambers are so formed and distributed that they do not interfere with the operation of screwing the tubes into the base C, even if said tubes are brought close together.

60 I do not claim as my invention a radiator-tube provided with a diaphragm, such having been in use for many years, and is shown, for example, in Patent No. 178,190.

65 What I claim as new, and desire to secure by Letters Patent, is—

70 The combination of a radiator-tube having the inside diameter of its body larger than that of its foot, and the body provided with grooved projections extending inwardly beyond the inner surface of the foot, and slidably 75 elastic diaphragm held in the grooved projections by its inherent elasticity, the distance between the grooved projections being less than the width of the diaphragm, substantially as described.

80 In testimony whereof I have hereunto set my hand and seal in the presence of two subscribing witnesses.

THOMAS P. HARDY. [L. S.]
